Max. & Shall Inventor

By his Attorney Martin Jonathan

UNITED STATES PATENT OFFICE.

MAX A. SKALL, OF NEW YORK, N. Y.

DISPENSER FOR PAPER NAPKINS.

1,209,054.

Specification of Letters Patent. Patented Dec. 19, 1916.

Application filed November 1, 1915. Serial No. 58,980.

To all whom it may concern:

Be it known that I, MAX A. SKALL, a citizen of the United States, and residing at New York city, in the county and State of New York, have invented certain new and useful Improvements in Dispensers for Paper Napkins, of which the following is a specification.

This invention relates to improvements in receptacles for storing and dispensing of paper napkins and similar articles, so that only one of these articles can be touched by the person using the same and the articles be dispensed in a sanitary and economical manner.

With the above and other objects in view the present invention consists of certain novel details of construction and arrangements of parts hereinafter described and particularly set forth in the appended claims.

Reference is to be had to the accompanying drawings, forming a part of this specification, in which—

Figure I is a plan view of my napkin dispenser. Fig. II is a sectional elevation taken on the line A—A of Fig. I. Fig. III is a side elevation of the napkin dispenser. Fig. IV is a transverse section on the line B—B of Fig. I. Fig. V is an enlarged detail section of the top and sides on the line B—B of Fig. I showing the arrangement of napkins in the dispenser. Fig. VI is a section through a side plate on line C—C of Fig. V to show the locking mechanism. Fig. VII is a front elevation of Fig. VI.

Similar letters of reference indicate corresponding parts throughout the various figures.

Referring to the drawings 1 represents the rectangular bottom of a casing which rests on rubber buffers 2 to hold the case a short distance above the supporting surface and to avoid scratching of the latter or undue noise. The bottom plate consists of a rectangular frame, 1^a preferably made of U-shaped cross section into which a plate 1^b of wood or any other suitable material is framed, the upper surface of this plate has a metallic covering 1^c. The plates 3 form the vertical ends and plates 4 the vertical sides of the casing these plates are made in a similar manner as the bottom, but the U-shaped channels preferably hold glass plates to make the case transparent; the lower edges 3^a and 4^a of the side plates are preferably

soldered to the frame 1^a of the bottom. The top of the case consists of two parallel plates 5, arranged lengthwise of the case and leaving an opening or slot 6 between their inner edges 5^a parallel to the longitudinal axis of the case. The outer edges 5^b of these plates overlap the outsides of plates 4 slightly; these edges as well as edges 5^a are preferably rounded and polished. Plates 5 are held together by means of U-shaped channels 7 running transversely at the ends of the case above plates 3 and the channels 7 are tied together by the longitudinal rods 8 which run longitudinally along the upper outside edges of plates 4 and are soldered or fastened in other suitable manner to the ends 7^a of channels 7. These rods also serve to secure the cover against transverse motion. The edges 5^a forming slot 6 are held by the required distance apart by means of a resilient, flat tongue piece 9 which is of the same width as the opening of the slot and fastened by a rectangular bend to the inner surface of channels 7. The body part of tongue 9 is provided with a suitable aperture 9^a which fits over and engages a hump 3^c which protrudes slightly from the inner legs of channels 3^b of sides 3. The lowest edge 9^b of tongue 9 is slightly curved away from the inner surface of sides 3. The upper part of tongue 9 is provided with a pin 10 preferably riveted thereto and protruding through an aperture of channel 7 to the outside of the cover. A pile of paper napkins folded one into the other so that their crease falls alternately to the right or left as shown in Fig. V is placed inside of this casing one edge of the uppermost napkin protruding through the slot 6. The napkins rest on a plate 11 which is supported on springs 12. These springs are flattened out along the bottom of the case when the latter is full of napkins, they take the position shown in full lines in Fig. II when the case is about half empty and the position indicated by dotted lines in the same figure when the case is entirely empty.

The operation of the napkin dispenser is probably evident by the foregoing description but attention should be called to the fact that the cover snaps into its place after being pressed in and remains there. Pressing on the ends of pins 10 will press aperture 9^a out of engagement with hump 3^c and the cover may again be lifted. Should it be desired however, to lock the case against

undue access, the pins 10 may be omitted and the cover can only be lifted by means of a key 13 which is inserted through slot 6, the hook of this key 13^a engages the edge 9^b 5 and lifts the aperture 9^a out of engagement with hump 3^c thus opening the cover. When in use the edge 14 of the uppermost napkin is pulled out and the friction between the folds of the 1st and 2d napkin pulls the 10 front edge of the second napkin 15 through the slot into the position indicated by dotted lines in Fig. V which is now ready for use and so on until the case is emptied.

From the foregoing it will be clear that 15 my new napkin dispenser has many advantages, it is possible to touch only one napkin at a time which is not only an advantage for its sanitary reasons but also effects a great saving of napkins, a considerable item for restaurants, lunch rooms, soda counters, etc. The construction of the sides and top plate, and especially the edges of the slot of highly polished glass facilitates the cleaning and enhances the sanitary 20 properties. The ease of opening when so desired and the means for making the opening of the receptacle harder for those not entitled thereto also effects the saving of napkins and the sanitary qualities. All these 25 advantages are made possible by the combination of the parts of this invention which I have thus described.

What I claim as new and desire to secure by Letters Patent is:

35 1. In a dispensing apparatus for folded paper articles a casing consisting of a base plate, vertical side plates and a removable cover plate formed by two separate parallel bars, joined at their ends by transverse 40 braces to leave a central opening between the inward edges of said bars for the extraction of articles from said casing, and means attached to said braces to fasten said cover plate to the side plates of the casing against 45 uplift.

2. In a dispensing apparatus for folded paper articles a casing consisting of a base plate and vertical side plates, a top plate,

removably fastened to said side plates and consisting of two parallel bars held a distance apart by gage pieces inserted transversely between said bars near their end, said gage pieces being adapted to prevent longitudinal motion of said cover plate.

3. In a dispensing apparatus for folded 55 paper articles a base plate and vertical side plates forming a casing open at its upper plane, a cover plate for said casing consisting of two parallel bars joined by transverse braces at their ends, to leave a longitudinal 60 opening between their inner parallel edges and means attached to said braces to prevent motion of said cover plate longitudinally, transversely or vertically.

4. In a dispensing apparatus for napkins 65 and similar articles a casing, consisting of a rectangular bottom section and framed transparent plates forming the sides of the casing, a top plate removably fastened to said side plates, said top plate consisting of 70 two separate parallel bars, held a distance apart from each other by transverse braces connected to the end sections of said bars, said braces being joined longitudinally by rods forming means to secure the top plate 75 against transverse motion.

5. In a dispensing apparatus for folded 80 paper articles, a casing consisting of transparent side plates, each side plate being surrounded by a frame of U shaped channels, a top plate removably held on said side plates, and consisting of two bars of transparent material joined at their ends by a transverse bar and leaving a central open space between these bars for the extraction 85 of the paper articles from said casing.

6. In an apparatus of the kind described, a casing, a removable cover plate on said casing, consisting of two separate, parallel bars, a frame attached to the edges of said bars, 90 to hold them in alinement, leaving an opening between said bars for the extraction of articles from said casing and means attached to said frame to fasten said cover plate to the casing.

MAX A. SKALL.
